UNITED STATES PATENT OFFICE.

LEO D. FELTEN, OF ST. PAUL, MINNESOTA.

COLLAPSIBLE PAPER SHIPPING BASKET.

Application filed October 25, 1926. Serial No. 144,115.

The object of this invention is to provide a collapsible paper shipping basket to replace the more awkward and expensive wood basket, now used.

5 It is a further object of this invention to provide a basket having folding side members and a removable bottom member which may be folded with side members.

Another object of this invention is to provide a basket which may be cheaply constructed and easily and quickly set up in operative position or folded into collapsed position.

These and other objects and advantages of 15 the invention will be fully set forth in the following description made in connection with the accompanying drawings in which like reference characters refer to the same part throughout the different views, and in 20 which,

Fig. 1 is a perspective view of the basket set up in operative position.

Fig. 2 is a plan view of the basket in developed form.

25 Fig. 3 is a sectional view on line 3—3 as indicated by arrows.

Fig. 4 is a bottom plan view of basket in operative position.

Fig. 5 is a view in elevation looking at 30 the bottom side of basket showing same in partially collapsed position.

Referring to the drawings the basket is shown comprising of vertical side portions or panels 1 and vertical end panels 2, and 35 having a lower horizontal panel 3 secured to side panel 1^a and a retainer panel 4 secured to side panel 1^b and to end panels 2^a and 2^b.

This basket can be made from one piece 40 of material, preferably paper and in the embodiment of the invention illustrated, the same is shown as constructed from one piece of material, the upright portions of the basket have creases 5 to facilitate the folding between the side panels 1 and the end panels 2.

Lower panel 3 has crease 6 to aid in quickly and accurately folding support panel 3^a against the side panel 1^a. Lower panel 3 also has crease 7 to aid in folding same into 50 a horizontal position and crease 8 to help turn down flap 3^b so that same will fit into pocket 11, thereby holding basket in operative position. Retainer panel 4 has crease 9 to help in folding said panel toward side

55 panel 1^b, so as to form pocket 11, for retaining flap 3^b of panel 3. Panel 4 also has

creases 10 for bending flap 4^a of panel 4 against end panels 2. The flaps 4^a are glued or otherwise secured to end panels 2^a and 2^b so as to hold retainer panel in position, so 60 as to form pocket 11 between said panel and side panel 1^b. Side panel 1^b is provided with flap 1^c, which may be glued or otherwise secured to end panel 2^a, so as to form a basket of rectangular shape. 65

When the basket is to be used for shipping articles therein, the upper portion of basket, consisting of side and end panels, is bent into rectangular shape, support panel 3^a is folded against the inside of side panel 1^a and 70 lower panel 3 is bent to a horizontal position, placing flap 3^b into pocket 11, as shown in Fig. 3, thereby folding the blank into position to form a basket ready for use. The lower panel 3 is extended slightly upward 75 into the basket, so that side and end panels cannot swing about their vertical axes, when the basket is in operative position. When it is desired to fold the basket, flap 3^b is removed from pocket 11 and panel 3 is folded 80 against panel 1^a to which it is pivoted. The side and end panels 1 and 2 are moved about their vertical axis at the corners thereof so that the basket becomes substantially into one plane, the same being shown partially 85 collapsed in Fig. 5. The basket when in collapsed condition can be sent to the consignor to be filled with goods.

From the above description it is seen that I have developed an extremely simple and 90 efficient form of collapsible paper shipping basket. The same can be used for a wide variety of materials, when made in different sizes it will form a convenient shipping basket for various grocery articles, fruits, berries, etc. The device can be made of paper, which is easily procured and can be provided at low cost. The device is preferably of paper which can be suitably coated to withstand the chemical action of the goods 95 100 shipped.

It will of course be understood, that various changes may be made in the form, details and arrangement of the various members, without departing from the scope of my invention, which, generally stated, consists of a device capable of carrying out the objects set forth, such as shown and described and defined in the appended claims. 105

What I claim is:

110 1. A blank for paper baskets including a rectangular side member, end members ex-

tending from opposite edges of the side member and defined therefrom by fold lines, a second side member extending from the edge of one end member opposite the first side member and defined from said end member by a fold line, an end flap extending from the edge of the last mentioned side member opposite the end member to which it is attached, said flap being defined from said side member by a fold line, a bottom panel of rectangular form and having at its opposite edges flaps defined from the bottom panel by fold lines, one of said flaps extending from a remaining edge of the first mentioned side member and defined therefrom by a fold line, a retainer flap extending from a remaining edge of the second side member and defined therefrom by a fold line, and end engaging tabs extending from the ends of the retainer flap and defined therefrom by fold lines, said tabs being formed free from the adjacent second side member and end flap thereon, there being a slit formed therebetween.

2. A basket formed from a paper blank including a rectangular side member, end members extending from opposite edges of the side member and defined therefrom by fold lines, a second side member extending from the edge of one end member opposite the first side member and defined from said end member by a fold line, an end flap extending from the edge of the last mentioned side member opposite the end member to

which it is attached, said flap being defined from said side member by a fold line, a bottom panel of rectangular form and having at its opposite edges flaps defined from the bottom panel by fold lines, one of said flaps extending from a remaining edge of the first mentioned side member and defined therefrom by a fold line, a retainer flap extending from a remaining edge of the second side member and defined therefrom by a fold line, and end engaging tabs extending from the ends of the retainer flap and defined therefrom by fold lines, said tabs being formed free from the adjacent second side member and end flap thereon, there being a slit formed between the said tabs and the said side member and end flap, said box being formed by folding the ends and sides at right angles to each other and securing the end flap to the opposite end member, the flap of the lower panel connected to the side member being folded upwardly and inwardly against the side member, the lower panel being folded to extend across the box between the side and end members, the remaining flap of the bottom panel being folded to rest against the inside of the opposite side member, the retaining flap ends being folded at right angles to the retainer flap and the retainer flap itself being folded to extend into the box and rest against the sides of the last mentioned bottom panel flap.

LEO D. FELTEN.
